AUTOMATIC SPRAYING MACHINE

Herbert J. Pattison, Detroit, Mich., assignor to
 Briggs Manufacturing Company, Detroit,
 Mich., a corporation of Michigan

Application March 24, 1939, Serial No. 263,954

12 Claims. (Cl. 91—45)

This invention relates to paint spraying machines or devices and more particularly to an improved automatic spraying machine adapted to perform a variety of spraying operations.

Spraying installations having manually controlled stationary spray guns and conveyor for moving the work past such guns have been successfully used on large pieces such as automobile bodies, structural steel beams, large panels, and the like. However, installations of this character cannot be used for painting small pieces of odd shapes, such as various frames, bent pieces of molding, and the like, without prohibitively large waste of paint, space, and time. Therefore, spraying of such small pieces has been done by hand with resulting inefficiency, waste of time, material, and factory space. Such hand operations are also injurious to the health of the operators and give low volume of production.

One of the objects of the present invention is to provide an improved automatic paint spraying machine which can perform spraying operations on a variety of workpieces which heretofore had to be sprayed by hand.

Another object of the invention is to provide an improved automatic spraying machine which can be used for spraying such workpieces as bent pieces of molding, automobile window frames, and the like, and is adapted to spray the paint only over the surface of the workpiece and not on the conveyor, thereby eliminating the excessive waste of paint by preventing wasteful spraying of paint through the openings in the workpieces onto conveyor surfaces.

A further object of the invention is to provide an improved spraying machine which is substantially continuous and automatic in its operation and can be served by one operator only and yet have a high productivity and give uniform coats of paint on the workpieces.

A still further object of the invention is to provide an improved spraying machine which occupies very little space and yet gives a large volume of production.

A further object of the invention is to provide an automatic spraying machine having improved means which automatically bring the moving workpiece to a stop when it reaches a predetermined position, starts operation of the spraying gun, moves said gun around the workpiece following the configuration thereof, brings the gun back to its starting position, shuts the gun off, and moves the sprayed workpiece away from the spray gun.

Other objects of this invention will appear in

the following description and appended claims, reference being had to the accompanying drawings forming a part of this specification wherein like reference characters designate corresponding parts in the several views.

Fig. 1 is a perspective view of the automatic machine embodying the present invention, said machine being viewed from its delivery or finish end.

Fig. 2 is a plan view of a window frame or garnish molding which may be painted or sprayed in the automatic spraying machine of Fig. 1.

Fig. 3 is a sectional view taken in the direction of the arrows on the section plane passing through the section line 3—3 of Fig. 2.

Fig. 4 is a perspective side view of the machine illustrated in Fig. 1, the observer being presumed to look in the direction of the arrows from the line 4—4 of Fig. 1.

Fig. 5 is a fragmentary perspective view illustrating the improved automatic spraying machine, the observer being presumed to look at said machine down from the right-hand upper corner thereof as indicated by the arrow designated by the character "5" in the upper right-hand corner of Fig. 1.

Fig. 6 is a transverse vertical sectional view of the machine, said view being taken in the direction of the arrows on the section plane passing through the line 6—6 of Fig. 4.

Fig. 7 is a view partly in section showing in plan the spray gun moving chain, the observer being presumed to look down from the plane passing through the line 7—7 of Fig. 4.

Fig. 8 is a view illustrating solenoid means controlling the work conveyor switch, said view being taken in the direction of the arrows on the section line passing through the line 8—8 of Fig. 7.

Fig. 9 is a sectional view taken in the direction of the arrows on the section plane passing through the line 9—9 of Fig. 7 and illustrating the spray gun and the operative arrangement thereof.

Fig. 10 is an electric wiring diagram illustrating the electric circuit operating the improved automatic spraying machine embodying the present invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or ter-

minology employed herein is for the purpose of description and not of limitation, and it is not intended to limit the invention claimed herein beyond the requirements of the prior art.

In the drawings there is shown, by way of example, a spraying machine adapted for automatic spraying of workpieces such as frames, curved moldings and the like. The machine is termed "automatic," since the only manual operations in connection with operating this improved machine is loading and unloading of the workpieces on the work conveyor, all other operations being performed automatically by improved means performing predetermined functions.

The machine illustrated in the drawings and hereinafter described is adapted for painting by spraying a frame molding for a motor vehicle body, said molding being in the form of a rectangular frame with rounded corners. It will be understood, however, that machines constructed in accordance with the present invention may be used for painting or spraying a great number of articles of various shapes, and, in fact, the machine hereinafter described may be adapted for painting workpieces of configurations different than that of the above specified frame molding which may be done by changing the guiding means of the spray gun and properly arranging the location and operation of the relay and switch means.

The machine illustrated in the drawings comprises generally a work conveyor adapted to receive workpieces to be painted, at one of its ends and to discharge the same at its other end. Superjacent of said conveyor there is provided a movable spray gun adapted to be moved in a path corresponding to the configuration of the frame moldings to be sprayed. The work conveyor and a chain moving said gun are actuated with the aid of electric motors. There are also provided means for opening and closing air conduits of said gun at the beginning and at the end of the operative movement thereof around said path, for starting and shutting off the spray gun. The machine is provided with a plurality of switches and relays included in an electric circuit connected to a suitable source of electric energy and adapted to control the above mentioned electric motors. Said switches and relays are so arranged that the work conveyor moves only until a workpiece to be sprayed reaches a predetermined position under said spray gun, whereupon the conveyor motor is shut off and the workpiece comes to rest. At this point the electric motor actuating the gun moving chain is automatically started and the spray gun moves around said frame, means also being provided to open the air conduit thereby starting operation of the spray gun. When the spray gun reaches the end of its working movement, the gun chain actuating motor is switched off, and the spray gun is shut off. Simultaneously, the work conveyor motor is switched on and the work conveyor begins moving to carry the sprayed workpiece to the discharge end thereof and to bring the new workpiece into the spraying position under the spray gun.

Referring to the drawings and particularly to Figs. 1, 4 and 6, the spraying machine illustrated therein comprises a frame made up of a plurality of members forming a table having legs 15 and horizontal members 16. On said table there is operatively mounted an electric motor 17 connected drivingly through a gear box 18 effecting suitable speed reduction, sprocket wheel 19 en-

gaged by a chain 20 driving a second sprocket wheel 21 with a shaft 22 on which said sprocket wheel 21 is mounted. The shaft 22 has two intermediate size sprocket wheels 23 and constitutes a driving shaft of the work conveyor adapted to carry workpieces past the spray gun.

The work carrying conveyor generally indicated by the numeral 24 comprises two endless connectors, in the present instance chains 25, 10 driven by the sprocket wheels 23, said chains being passed around idler sprocket wheels 26 and large size idler sprocket wheels 27. There is provided four of such large idler sprocket wheels divided into pairs, each pair being operatively 15 mounted on a shaft 28 having ends journaled in bearings 29 secured to the lower horizontal members 16 of the table.

To the links of the chains 25 there are secured pieces 30 (see Fig. 5), the two opposing pieces of 20 the chains 25 being connected by means of a bar or rod 31. Since links of the chain 25 are relatively small, the bars 31 are arranged relatively close together, thus forming in effect a rather wide built-up flexible conveyor passing around 25 the sprocket wheels and driven by the electric motor 17. Thus, when the electric motor 17 operates it rotates a sprocket wheel 19. Rotation of said wheel 19 is transmitted by the chain 20 to the second sprocket wheel 21 and the shaft 22. The sprocket wheels 23 secured on the ends 30 of the driven shaft 22 drive the chains 25 and therefore the entire conveyor.

The work conveyor 24 is adapted to receive workpieces 32 which in the present instance 35 are garnish moldings such as are used in motor vehicle bodies. The moldings are of a substantially rectangular form, thus presenting workpieces of closed linear configuration. The workpieces 32 are located on said conveyor by means 40 of suitable means such as blocks 33 provided on the bars or rods 31.

The conveyor 24 is adapted to move intermittently and to receive workpieces at its receiving end, bring them to the spray gun generally indicated by the numeral 35 and to discharge said workpieces at its delivery end. Loading and unloading of the conveyor 24 is done by hand as was explained above.

Intermittent motion of the conveyor 24 is effected by opening and closing the electric circuit feeding the work conveyor motor 17, the opening of said circuit and consequently stopping the motor 17 being effected at the moment when a workpiece reaches a predetermined position under 50 the spray gun 35. In the present embodiment of the invention such switch is exemplified by the switching device 36 operated for performance of the above function by a relay 37 which relay is hereinafter termed "the first relay." Said first 55 relay is operated in turn by means of a photoelectric device, often referred to in the art as "an electric eye," said device including a projector 38 fed from an electric circuit supplying electric current brought to proper voltage and amperage with the aid of a transformer 39 connected to the electric source, in the present instance the regular power line. The projector 38 is adapted to throw a beam of light passing just above the conveyor and received by a screen of 60 a light sensitive device 40 operatively connected to said first relay 37. The beam of light is adapted to be intercepted by a workpiece when the same reaches a predetermined position, such 65 interception of the light beam causing the light sensitive device 40 to operate the first relay 37

and the switch 36 to open the electric circuit feeding the work conveyor motor 17.

Means for operating the spray gun 35 for performance of the predetermined functions thereof comprise, first, electric actuating means and, second, guiding means therefor. The electric actuating means comprise an electric motor 41 provided with a suitable gear box 42 effecting the desired rotative speed at the drive shaft 43 carrying a drive pinion 44, the rotation of which is transmitted with the aid of a chain 45 to a driven wheel 46. The wheel 46 is secured to a shaft 47 on the opposite end of which is secured a driving wheel 48 engaging a gun moving chain or conveyor 49. The gun moving chain 49 is adapted to move in a predetermined path corresponding to the configuration of the workpiece 32 which path is determined by the guiding means generally indicated by the numeral 50 and comprising a built-up templet of a configuration substantially similar to that of the workpiece 32. The chain 49 is connected with a gun 35 by means of an arm or link 51 adapted to move bodily with said chain 49 making one complete revolution as the chain makes one complete turn. The link 51 is secured to the gun in such a way as to rotate the same as said link moves around.

Fig. 6 illustrates various positions of the gun in the rotating movement thereof. It should be understood that the actual path of the gun although similar in its configuration to the configuration of the workpiece is considerably smaller than the workpiece. In many instances only rotation of the gun will be sufficient for spraying workpieces of enclosed configurations.

The gun 35 is carried by a head generally indicated by the numeral 52, said head being a structure providing three concentric conduits, 53, 53a, and 53b, the central conduit 53 having a connection for a rubber hose 54 connected to the paint supply tank 55. The paint from said conduit 53 is delivered to the spray gun through the hose 54a, see Fig. 5. The hose 56 is adapted to supply air under pressure through conduit 53a to the gun trigger while the hose 57 is an air line for the spray connected to the outer concentric conduit 53b. Said hoses 56 and 57 and conduits 53a and 53b continue in the form of hoses 56a and 57a leading to the spray gun 35, forming in effect continuous conduits from the source of air supply to the gun. It will be readily understood that the concentric conduits are formed as shown in Fig. 9 by concentric tubes connected to the gun and rotatable therewith. Although the hose lines 54, 56 and 57 are fixed against rotation with the head 52 they remain at all times in communication with the concentric tubes during any rotative movement thereof in response to corresponding movements of the gun.

The head 52 is rotatably carried by an arm 58 hingedly connected as shown at 59 to an arm 60 hingedly secured to the post 61 secured to the plate 62. The plate 62 carries the gun actuating and guiding means, and is in turn secured to the horizontal members 16 of the table or frame of the machine.

It will now be clear in view of the foregoing that the above described suspension of the gun 35 permits rotation as well as bodily movement thereof without binding the parts or twisting the hoses. The spray gun 35 may be of any suitable construction, and being in itself a well known device it need not be described in detail.

As already explained, there are provided means, which become active at the moment of stopping of the work conveyor, operating to switch on the spray gun motor 41, and also to start the spray gun 35 by opening an air valve 65 admitting air under pressure to said gun 35 through the air conduit 57. Said means comprise in the present embodiment of the invention a second relay 66 electrically connected to said light sensitive device 40, and to the power line through the switch 36a as shown in the diagram of Fig. 10. When the work conveyor stops, the second relay 66 switches on the gun conveyor motor 41 and energizes the solenoid 67 which overcomes under said conditions, the resistance of the spring 68.

On the gun moving chain 45 there is provided a pin or block 69 adapted to engage a hook 70 operated by an electric eye solenoid 71. The hook 70 is adapted to operate the switches 36 and 36a. A spring 72 is compressed when the hook 70 is caught by the moving pin 69, and when the hook being raised by the solenoid 71 is released, said spring expands, returning the switches 36 and 36a into the positions shown in Fig. 10. This causes switching on of the work conveyor motor 17 as explained. When, however, the solenoid 71 is de-energized and the hook 70 is engaged by the pin 69, the switches 36 and 36a are operated to stop the spray gun motor 41 and the gun moving chain 45. At the end of the movement of the gun moving chain 45, the above means operate to start the work conveyor, as already described, thus beginning a new operative cycle.

A general switch 73 is provided for the purpose of starting and stopping the entire machine. When said switch is closed the work conveyor begins moving. It is desirable to put a first workpiece on the conveyor when the same is still stationary, since if no workpieces are carried by the conveyor, it will move continuously, but the spray gun operating means will remain inactive.

Since the relays 37 and 66 are of a conventional design, the diagram of Fig. 10 is believed to be quite sufficient for those skilled in the art to effect proper connections of the devices combined, tracing of all circuits under the conditions mentioned being deemed unnecessary.

I claim:

1. In a spraying machine, a spray gun, a work conveyor operatively arranged with its working side in spraying proximity to said gun and adapted to move to a spraying position at said gun a workpiece of a substantially rectangular linear configuration; guiding means adapted to guide the spray gun in a path corresponding substantially to the configuration of the workpiece; an electric circuit including a source and an electric motor adapted to actuate said work conveyor, and a second electric motor adapted to actuate said spray gun in said path; means adapted to switch off said conveyor motor when said workpiece reaches its spraying position; and means for starting said spray gun motor when said conveyor stops, and starting said conveyor motor when the spray gun completes its path.

2. In a spraying machine, a bodily movable spray gun, a plurality of air conduits delivering air under pressure for operating said gun; a valve controlling said conduits; an electrically actuated work conveyor adapted to carry workpieces past said spray gun and to bring them successively into a spraying position thereat; an electrical

ly actuated flexible connector means for moving said gun in a path corresponding substantially to the configuration of said workpieces; photoelectric means controlled by the movement of the workpieces on said work conveyor and adapted to stop said conveyor when a workpiece reaches a predetermined spraying position with respect to said spray gun; a plurality of relays controlled by said photoelectric means and adapted to open electromagnetically said air conduits to start said gun when the work conveyor stops, to stop said gun moving means when the path of the gun is completed simultaneously shutting off said gun and starting again said work conveyor for carrying away the sprayed workpiece and bringing up another workpiece for starting the next operative cycle.

3. In a spraying machine, a bodily movable spray gun, a plurality of air conduits delivering air under pressure to said gun for operating the same; a valve adapted to interrupt said conduits for shutting off said gun; a work conveyor adapted to carry workpieces past said gun and to bring them one after another into a spraying position thereat; an electric motor adapted to actuate said conveyor; a flexible connector means adapted to move said gun along a path corresponding to the configuration of the workpieces; an electric motor adapted to actuate said connector; photoelectric means including a device producing a light beam interceptable by a workpiece reaching a predetermined position with respect to said gun at the initial position thereof, a plurality of interconnected relays and switches controlled by said photoelectric means and adapted to stop said conveyor motor by opening the electric circuit thereof when said light beam is intercepted by a workpiece, to open said air conduits electromagnetically for starting operation of the gun, and to start said flexible connector motor by closing the electric circuit thereof for actuating said flexible connector means and moving said gun in said path.

4. In a spraying machine, a spray gun, a plurality of air conduits delivering air under pressure to said gun for operating the same; a valve adapted to interrupt said conduits for shutting off said gun; a work conveyor adapted to carry workpieces past said gun; an electric motor adapted to actuate said conveyor; a flexible connector means adapted to move said gun along a path corresponding to the configuration of the workpieces; an electric motor adapted to actuate said connector; photoelectric means including a device producing a light beam interceptable by a workpiece reaching a predetermined position with respect to said gun at the initial position thereof; relay-and-switch means controlled by said photoelectric means and adapted to stop said conveyor motor when said light beam is intercepted by a workpiece to bring said workpiece to rest for spraying, and to start said conveyor motor after the spraying operation is completed.

5. In a spraying machine, a bodily movable spray gun, a plurality of air conduits delivering air under pressure to said gun for operating the same; a valve adapted to interrupt said conduits for shutting off said gun; a work conveyor adapted to carry workpieces past said gun and to bring them one after another into a spraying position thereat; an electric motor adapted to actuate said conveyor; a flexible connector means adapted to move said gun along a path corresponding to the configuration of the workpieces; an electric motor

adapted to actuate said connector; photoelectric means including a device producing a light beam interceptable by a workpiece reaching a predetermined position with respect to said gun at the initial position thereof; a relay-and-switch means controlled by said photoelectric means and adapted to stop said conveyor motor by interrupting the circuit thereof when said light beam is intercepted by a workpiece, to open said air conduits electromagnetically for starting operation of the gun, to start said flexible connector motor by closing the electric circuit thereof for actuating said flexible connector means and moving said gun in said path, to stop the connector motor by opening the electric circuit thereof when the gun reaches the end of said path, simultaneously shutting off said gun and starting said work conveyor motor by closing the electric circuit thereof.

6. In a spraying machine having a bodily movable spray gun, means for moving said gun along a closed curvilinear path, a conveyor adapted to move a workpiece of a closed curvilinear configuration substantially corresponding to that of said gun path past said gun, an electric motor actuating said conveyor, an electric circuit including a source into which said motor is interposed for operation, a photoelectric device adapted to break said circuit and to stop said motor and, consequently, the conveyor when said piece reaches a predetermined position near said spray gun, thus bringing the workpiece to rest for spraying, means controlled by said device and adapted to move the operating gun around its curvilinear path thus following the periphery of said workpiece, and means adapted to close said circuit after the spraying operation is completed thus starting said motor for actuating the conveyor and carrying said workpiece away from said gun.

7. In a spraying machine, a spray gun; an electrically actuated work conveyor adapted to move a workpiece of a closed linear configuration to a spraying position at said gun, means actuated by said conveyor when the workpiece reaches spraying position, said means being adapted to stop said conveyor and consequently said workpiece at said gun and to hold it stationary until the spraying operation is completed; guiding means for said gun so located with respect to the workpiece when the same is held stationary that when the spray gun is moved along said guiding means the spray follows substantially the configuration of the workpiece, the configuration of said guiding means being substantially similar to that of the workpiece; and an electrically actuated flexible member for moving said gun along said guiding means while the workpiece is held stationary.

8. In a spraying machine, a spray gun; an electrically actuated work conveyor adapted to move a workpiece of a curved linear configuration to a spraying position at said gun, means actuated by said conveyor when the workpiece reaches spraying position, said means being adapted to stop said conveyor and consequently said workpiece at said gun and to hold it stationary until the spraying operation is completed; guiding means for said gun having configuration substantially similar to the configuration of the workpiece and so located with respect to the stationary held workpiece that when the spray gun is moved along said guiding means the spray follows substantially the configuration

of the workpiece; an electric circuit including a source and an electric motor; a flexible endless member drivingly connected to said motor and adapted to move said gun along said guiding means while the workpiece is held stationary.

9. In a spraying machine, a spray gun; an electrically actuated work conveyor adapted to move a workpiece of a curved linear configuration to a spraying position at said gun, means actuated by said conveyor when the workpiece reaches spraying position, said means being adapted to stop said conveyor and consequently said workpiece at said gun and to hold it stationary until the spraying operation is completed; guiding means for said gun having a configuration substantially similar to that of the workpiece and so located with respect to the workpiece when the same is held stationary and the spray gun is moved along said guiding means, the spray follows substantially the configuration of the workpiece; an electric circuit normally kept open and including a source and an electric motor electrically interposed in said circuit, an endless chain drivingly connected to said motor and adapted to move said gun along said guiding means; and means adapted to close said circuit when the workpiece reaches its spraying position, and to open said circuit again after said gun completes its movement along said workpiece and returns to its original position.

10. In a spraying machine, a bodily movable spraying gun, a work conveyor operatively arranged adjacent said spraying gun and adapted to move workpieces of curvilinear configuration to and past said gun, means adapted to hold the workpieces in predetermined positions on said conveyor, means adapted to move said conveyor intermittently to bring the workpieces successively to said gun, electric means adapted to stop said conveyor when a workpiece reaches a predetermined position near said gun in order to hold the workpiece in spraying proximity to said gun until the spraying operation is completed, valve means controlled by said conveyor to cause operation of said gun when the conveyor stops, and guiding means for said gun so arranged with respect to the workpiece on said conveyor in proximity to said gun that when the spray gun is moved along said guiding means

the spray from said gun follows substantially the configuration of said workpiece, and means for moving said gun along said guiding means while the workpiece is being held stationary.

5 11. In a spraying machine for spraying workpieces of uniform sizes, a spray gun bodily movable along a curvilinear path lying in a substantially straight plane and substantially corresponding to the configuration of the workpiece to be sprayed, an intermittently moving endless conveyor adapted to receive workpieces and to bring them one after another into a position in spraying proximity to said gun and to stop in such a position having the respective workpiece 10 in such spaced relationship to the gun that when said gun moves along its path the spray of the gun substantially follows the configuration of said workpiece, means stopping said conveyor as a workpiece reaches said position, and means 15 beginning the moving of said gun for spraying said workpiece as said conveyor stops.

12. In a spraying machine for spraying workpieces of uniform sizes, a spray gun bodily movable along a curved closed path substantially corresponding to the configuration of the workpieces to be sprayed, valve means controlling the opening and closing of the spray of said gun, an endless conveyor adapted to receive workpieces to be sprayed and to bring them successively one after another into a spraying position 20 at said gun and when stopped to hold a workpiece in such position for a period of time sufficient for said gun to travel around its path spraying said workpiece, an electric motor actuating said conveyor, an electric circuit into which said motor is electrically interposed for operation, a source of electric energy interposed in said circuit, a photoelectric device adapted to be actuated by said conveyor when a workpiece reaches said spraying position to break said motor circuit and to stop said motor and said conveyor in order to hold the workpiece stationary until the spraying operation is completed, and a relay means adapted to be controlled by said photoelectric device and to actuate said gun valve means when said conveyor 25 stops.

HERBERT J. PATTISON.

CERTIFICATE OF CORRECTION.

Patent No. 2,281,169.

April 28, 1942.

HARBERT J. PATTISON.

It is hereby certified that error appears in the printed specification of the above numbered patent requiring correction as follows: Page 4, first column, line 11, claim 2, before "when" insert --moving means--; and that the said Letters Patent should be read with this correction therein that the same may conform to the record of the case in the Patent Office.

Signed and sealed this 23rd day of June, A. D. 1942.

Henry Van Arsdale,

(Seal)

Acting Commissioner of Patents.
